UNITED STATES PATENT OFFICE.

JOHN I. KELLEY, OF PHILADELPHIA, PENNSYLVANIA.

GARTER-FASTENING.

1,346,657.

Specification of Letters Patent. Patented July 13, 1920.

Application filed March 1, 1920. Serial No. 362,498.

To all whom it may concern:

Be it known that I, JOHN I. KELLEY, a citizen of the United States, residing in Philadelphia, Pennsylvania, have invented 5 certain Improvements in Garter-Fastenings, of which the following is a specification.

The object of my invention is to improve the construction of a fastening for garters, and like articles, which will hold under all 10 circumstances, and which can be easily applied and detached.

In the accompanying drawings:

Figure 1 is a perspective view of a garter illustrating my invention; 15 Fig. 2 is a side view, showing the parts of the fastening detached;

Fig. 3 is a view showing the parts attached; and

Fig. 4 is a view showing the location of 20 the pin in the inclined slot when the garter becomes slack.

The garter illustrated in the drawing is one to be applied to the calf of the leg and is used for holding men's half-hose. 1 is a 25 triangular piece of fabric. 2 is an elastic band having a loop 3 at one end and an adjustable plate 4 to which the free end of the band is attached, and which forms the loop. In the loop is one portion 5 of my 30 proved fastening. 6 is a plate attached to the triangular piece 1 by stitching, in the present instance, as shown in Fig. 1. The plate has a headed pin 7 adapted to the slot 8 in the part 5. It will be noticed that this 35 part 5 also has a narrow, elongated slot 9 through which the fabric of the loop 3 extends. This slot is connected with an enlarged slot 10 of sufficient width to allow the head 11 of the pin 7 to pass readily 40 through it. This slot 10 is connected to the narrow slot 8 by an inclined slot 12 of the width of the narrow slot 8 so that, if the pin 7 should pass into the slot 12, it cannot be detached from the part 5 unless it passes into 45 the enlarged slot 10.

By arranging the slot 12 at the angle shown and having the enlarged slot some distance from the slot 8, any slack movement

of the pin will not detach the garter and even when the pin is in the slot 12, as in Fig. 50 4, the slot being inclined the pin has a tendency to return to the slot 8 so that under all conditions one end of the garter will not become detached from the other unless the pin enters the enlarged slot 10.

55

In the present instance, secured to the extension 13 of the triangular portion 1 is a looped wire 14 adapted to engage a headed pin 15 carried by a tab 16, also secured to the extension 13. This fastening engages 60 the stocking.

While I have described the fastening as particularly adapted to certain types of garters, it will be understood that it can be used with other types of garters, or similar 65 devices, where such a fastener is desirable.

I claim:

1. The combination in a fastener, of two sections, one section having a headed pin, the other section having a narrow longitudinal slot at the center; an enlarged slot for the passage of the head of the pin of the other section, said slot being at one side and back of the longitudinal slot; and a diagonal narrow slot connecting the large slot with 75 the rear end of the narrow longitudinal central slot.

2. The combination of a garter having a body section; an elastic band; a fastening device consisting of two sections, one section 80 having a slot through which the elastic band extends, the other section having a bar around which the stitching is passed to secure this section to the garter; a headed pin on this section, the other section having an 85 enlarged slot at one end to allow for the passage of the head of the pin of the other section and having a centrally located longitudinal, narrow slot; and a diagonal slot connecting the wide slot with the narrow 90 slot, said diagonal slot also being narrow, preventing the withdrawal of the pin, the wide slot communicating with the narrow slot through which the band of the garter is passed.

JOHN I. KELLEY.
